ROBERT W. KALTENBACH, OF BEDFORD, AND JUSTIN GRIESS, JR., OF CLEVELAND, OHIO.

CLAM-SHELL BUCKET.

No. 823,412.

Specification of Letters Patent.

Patented June 12, 1906.

Application filed October 25, 1905. Serial No. 284,356.

To all whom it may concern:

Be it known that we, ROBERT W. KALTENBACH, residing at Bedford, and JUSTIN GRIESS, Jr., residing at Cleveland, county of 5 Cuyahoga, and State of Ohio, citizens of the United States, have invented certain new and useful Improvements in Clam-Shell Buckets; and we do hereby declare the following to be a full, clear, and exact description 10 of the invention, such as will enable others skilled in the art to which it pertains to make and use the same.

This invention relates to improvements in clam-shell buckets comprising two oppositely-arranged scoops, trays, or bucket-sections having cutting edges at the bottom and forward ends and pivotally supported as required to render them capable of being swung from and toward each other to open and close 20 the bucket, respectively.

One object of this invention is to so relatively arrange the parts of the actuating mechanism of the bucket as will bring the center of gravity of the bucket low enough 25 to prevent tipping of the bucket when the bucket is landed on an uneven pile of material.

Another object is to pivotally attach the bars or links, which are pivotally connected 30 to the rear portions of the trays, to the tray-actuating levers, with the pivotal connections between each bar or link and the connected lever arranged below and at the sides of the axis of a bail with which the bucket is 35 centrally provided so as to advantageously place the trays relative to the pile or bed of material to be excavated or operated upon when the bucket is open, with the relative arrangement of the parts furthermore such 40 that the bars or links pivotally connected to each tray will cross the bars or links pivotally connected to the other tray below the bail and not depend below the lower surfaces of the levers at a point in under the bail when 45 the bucket is open.

With these objects in view this invention consists in certain features of construction and combinations of parts hereinafter described, and pointed out in the claims.

50 In the accompanying drawings, Figure 1 is a side elevation of a clam-shell bucket and connected bucket-operating mechanism embodying our invention, and in this figure the bucket is shown closed. Fig. 2 is a right-

hand side elevation relative to Fig. 1. Fig. 3 55 is a top plan relative to Fig. 1. Fig. 4 is a side elevation of the bucket and connected mechanism with the bucket open.

Referring to the drawings, A and A' indicate two oppositely-arranged trays which 60 form the body portion of our improved bucket. The trays A and A' swing rearwardly from or forwardly toward each other according as the bucket is opened or closed. The bucket illustrated is shown closed in Figs. 65 1, 2, and 3 and open in Fig. 4. Each tray is provided at its rear end and near the top thereof with an axle a, which is arranged horizontally and transversely of the tray. The axes a of the two trays are parallel and ar- 70 ranged in the same plane horizontally. The trays A and A' in opening and closing swing in a vertical plane upon the axles a.

Each axle a has bearing in the rear ends of two parallel bars B, which are arranged at 75 opposite sides, respectively, of the tray journaled on the said axle and in the closed position of the bucket, as shown in Figs. 1 and 3, extend upwardly, as well as forwardly, relative to the said tray. It will be observed, there- 80 fore, that the trays A and A' have bearing on the axles a and that the latter have bearing in the rear ends of the bars B. The bars B are pivoted at their forward ends, as at b, horizontally and parallel with the axles a to 85 the lower ends of the end members 12 and 13 of a bail.

Two levers C and C are operatively attached to the tray A. The levers D and D are operatively attached to the tray A'. The levers 90 C C and D D are fulcrumed horizontally and parallel with the axes of the trays to the end members 12 and 13 of a bail whose upper and central portions comprise two horizontal axles 14 and 15, which are arranged in the same 95 plane horizontally and parallel with each other and with the axles a. The axles 14 and 15 have bearing in the upper ends of both end members 12 and 13 of the bail. The levers C C and D D have their fulcrums 100 coincident and formed by horizontally-arranged axles 16 and 17, which extend through the bail members 12 and 13, respectively, at the lower ends of the said bail members. The axles 16 and 17 are parallel with the axes 105 of the trays and arranged in line endwise. The bail members 12 and 13 are tied together and braced apart above the fulcrums of the

levers C and D (see Figs. 2 and 3) by a frame or web 8, formed in any approved manner and rigid with the said bail members. The levers C C and D D extend forwardly and upwardly from the connected tray, and the levers C C cross the levers D D at the fulcrums of the levers and above the connection of the said levers with the trays. The levers C C are shown pivoted at their lower ends, as at 18, to opposite sides, respectively, of the tray A horizontally and parallel with the axis of the said tray at the upper portion of the forward end of the tray. The levers D D are pivoted at their lower ends, as at 20, to opposite sides, respectively, of the tray A' horizontally and parallel with the axis of the said tray at the upper portion of the forward end of the tray. It will be observed, therefore, that the levers C and D at one side of the 25 bucket are fulcrumed to the bail member 13 by means of the axle 16, that the levers C and D at the opposite side of the bucket are fulcrumed to the bail member 12 by means of the axle 17, that the pivotal connections between the bars B and the levers C and D are arranged below, but at opposite sides, respectively, of the fulcrums of the levers C and D, and that when the bucket is closed, as shown in Fig. 1, the bars B which connect 30 the levers C with the tray A are wholly arranged at one side of the axes of the levers C and D and at the outer sides of the levers C and the bars B which connect the levers D with the tray A' are wholly arranged at the 35 opposite side of the said axes and at the inner side of the levers D.

The levers C and C are connected together and braced apart at and above their axes (see Figs. 2 and 3) by a frame c, which is 40 journaled upon the axles 16 and 17 and connected at the top to the said levers by axles 22, which are horizontally arranged parallel with the axes of the said levers and in line endwise and attached to and borne by the 45 said frame and the said levers.

The levers D and D are connected together and braced apart at and above their axes (see Figs. 2 and 3) by a frame d, which is 50 journaled upon the axles 16 and 17 and connected at the top to the said levers by axles 24, which are horizontally arranged parallel with the axes of the said levers and in line endwise and attached to and borne by the 55 said frame and the said levers. Upon each axle 22 is loosely mounted a guide-sheave 23, and upon each axle 24 is loosely mounted a guide-sheave 25.

Two bucket-closing cables G and G' are suitably attached at one end to the axle 14, 60 thence lead downwardly to and around the sheaves 25, connected with the upper ends of the levers D, thence lead in under the sheaves 23, connected with the upper ends of the levers C, thence lead into engagement 65 with guide-sheaves 26, which are loosely

mounted on the axle 15, and thence lead to winding-drums or means (not shown) employed in operating the said cables. The levers C are provided at their upper ends with guards 27, arranged to prevent displacement 70 of the cables G from the sheaves 23. The levers D are provided at their upper ends with guards 28, arranged to prevent displacement of the cables G from the sheaves 25. The upper portions of the levers D are provided with laterally-projecting stop-forming lugs 30, which are engaged by the levers C when the bucket is full open and limit the movement of the levers as required in operating the levers to separate the trays A and A' in opening the bucket.

Upon each axle a between the bars B, connected with the said axle, is journaled a clevis L. Two bucket-holding cables R and R' are suitably attached to the clevis of the different 85 axles a and a', respectively; and lead from the connected clevis upwardly to and in under guide-sheaves 34 and 35, respectively, which are loosely mounted on the axles 14 and 15, respectively. (See Figs. 2 and 3.) The 90 axles 14 and 15 are provided with a guard 32, arranged to prevent displacement of the cables R from the sheaves 34 and 35, which guard extends over the said sheaves and is provided with holes 33, arranged to accommodate the extension of the said cables through the guard upwardly from the sheaves. The cables R are operated in any approved manner.

Cable-operating devices are too well known 100 in the art to require illustration and description in this application.

The axle 15 is provided with guards 36, arranged to prevent displacement of the cables G from the sheaves 26.

It will be observed that the bucket-trays A and A' are, when the bucket is laden and closed and suspended over a pile or bed of material, opened by the gravity of the bucket and contents upon holding the cables R and releasing the bucket-closing cables G, that the bucket, when open, is closed by actuating the levers C and D upon winding up or pulling on the cables G, and that when the bucket is open, as shown in Fig. 4, the bars B attached to each tray cross the bars B attached to the other tray below the bail and do not depend below the lower surfaces of the levers.

What we claim is—

1. In a clam-shell bucket having two trays arranged to swing toward or from each other according as the bucket is opened or closed, the combination of the trays; a bail arranged centrally of the bucket; laterally-spaced levers operatively attached to one of the trays and laterally-spaced levers operatively attached to the other tray, said levers being all pivotally connected with or fulcrumed to the bail and the levers attached to each tray 130

crossing the levers attached to the other tray at the fulcrums of the levers; bars pivotally connected to the trays rearwardly of the levers, and the bars pivotally connected to each 5 tray being pivoted also to the levers attached to the other tray at a point below the axes of the levers, and means for operating the levers, and the relative arrangement of the parts being such that when the bucket is 10 closed the bars attached to the levers secured to one of the trays are wholly arranged at one side of the axes of the bail and the bars attached to the levers secured to the other tray are wholly arranged at the opposite side 15 of the said axis.

2. In a clam-shell bucket having two trays arranged to swing toward or from each other according as the bucket is opened or closed, the combination of the trays; a bail arranged 20 centrally of the bucket; laterally-spaced levers operatively attached to and at the forward end of one of the trays and laterally-spaced levers operatively attached to and at the forward end of the other tray, said levers 25 being all pivotally connected with or fulcrumed to the bail, and the levers attached to each tray crossing the levers attached to the other tray at the fulcrums of the levers; bars pivoted to one of the trays rearwardly and at 30 the outer sides of the levers attached to the respective tray, and bars pivotally connected to the other tray rearwardly of and at the inner sides of the levers attached to the last-mentioned tray, with the bars extending from the 35 connected tray toward and pivoted also to the levers attached to the other tray at a point below the axes of the levers, and means for operating the levers, all arranged and operating substantially as shown, for the purpose 40 specified.

3. In a clam-shell bucket having two trays arranged to swing toward or from each other according as the bucket is opened or closed, the combination of the trays; a bail arranged 45 centrally of the bucket; levers operatively attached to and at the forward end of one of the trays and levers operatively attached to and at the forward end of the other tray, said levers being all fulcrumed to the bail and the 50 levers attached to each tray crossing the levers attached to the other tray at their fulcrums; bars pivotally connected to the trays rearwardly of the levers, with the bars pivotally supported also below but in suitable 55 proximity to the axes of the levers, and means for operating the levers, and the parts having such relative arrangement that when the bucket is closed the bars attached to the levers secured to one of the trays are wholly 60 arranged at one side of the axis of the bail and the bars attached to the levers secured to the other tray are wholly arranged at the opposite side of the said axis.

4. In a clam-shell bucket having two trays 65 arranged to swing toward or from each other

according as the bucket is opened or closed, the combination of the trays; an upright bail arranged centrally and transversely of the bucket and having end members arranged a suitable distance apart laterally; levers operatively attached to the trays at the forward ends of the trays and pivotally connected or fulcrumed to the lower portions of the end members of the bail; bars pivotally connected to the rear portions of the trays and pivotally connected to the levers below the fulcrums of the levers, and means for operating the levers, and the pivotal connections between each lever and the connected bar being arranged below the axes of the levers, with the relative arrangement of the parts such that when the bucket is open the bars or links pivotally connected to each tray cross the bars or links pivotally connected to the other tray below the bail and are arranged wholly above the lower surfaces of the levers. 70 75 80 85

5. In a clam-shell bucket having two trays arranged to swing toward or from each other according as the bucket is opened or closed, the combination of the said trays; an upright bail arranged centrally of the bucket; levers operatively attached to the trays at the forward ends of the trays and pivotally connected or fulcrumed to the bail; bars pivotally connected to the rear portions of the trays 90 and pivoted to the levers below the fulcrums of the levers, and means for operating the levers, and the pivotal connection between each bar and the connected lever at one side of the axes of the levers and the pivotal connection between each bar and the connected lever at the opposite side of the axes of the levers being arranged both below but at opposite sides respectively of and equidistantly from the said axes so that when the bucket is 95 100 105 open the bars or links pivotally connected to each tray cross the bars or links pivotally connected to the other tray below the bail.

6. In a clam-shell bucket having two trays arranged to swing from or toward each other 110 according as the bucket is opened or closed, the combination of the trays; a bail arranged centrally of the bucket and provided at the top with sheaves; upright levers operatively attached to the forward portions of the trays 115 and supported from the bail; sheaves borne by the levers at the upper ends of the levers; bars pivoted at one end to the rear portions of the trays and pivotally supported at the other end; cables attached to the upper portion of the bail, thence leading to and around the sheaves of the lever or levers attached to one of the trays, thence leading to and in under the sheaves of the lever or levers attached to the other tray, and thence in under the 120 aforesaid sheaves of the bail; and guards supported from the bail and arranged to prevent displacement of the cables from the last-mentioned sheaves. 125

7. In a clam-shell bucket having two trays 130

arranged to swing from or toward each other according as the bucket is opened or closed, the combination of the trays; a bail arranged centrally of the bucket and having end members which are arranged a suitable distance apart laterally and an upper central portion comprising two parallel axles extending between the end members of the bail; two upright levers operatively attached to opposite sides respectively of the forward portions of one of the trays and fulcrumed to the different end members respectively of the bail; two upright levers operatively attached to opposite sides respectively of the forward portion of the other of the said trays and fulcrumed to the different end members respectively of the bail and crossing the first-mentioned levers, with the axes of all of the said levers parallel with the axes of the trays; sheaves borne by the levers at the upper ends of the levers; bars pivotally connected at one

end to the rear portions of the trays and pivotally supported at the other end; two sheaves on one of the aforesaid axles a suitable distance apart longitudinally of the respective 25 axle; cables attached to the other of the aforesaid axles, thence leading to and around the sheaves of the levers attached to one of the trays, thence leading to and in under the sheaves of the levers attached to the other tray, and thence in under the aforesaid axle-sheaves, and guards mounted on the last-mentioned axles and arranged to prevent displacement of the cables from the axle-sheaves. 30

Signed by us at Cleveland, Ohio, this 21st day of October, 1905.
